D. G. JOHNSTON

MORTAR RETAINER FOR BUILDING BLOCKS

Filed June 15, 1922

Inventor

David G. Johnston
by Orwig & Shague, Atty's

UNITED STATES PATENT OFFICE.

DAVID G. JOHNSTON, OF CLAYWORKS, IOWA.

MORTAR RETAINER FOR BUILDING BLOCKS.

Application filed June 15, 1922. Serial No. 568,369.

To all whom it may concern:

Be it known that I, DAVID G. JOHNSTON, a citizen of the United States, and a resident of Clayworks, in the county of Webster and State of Iowa, have invented a certain new and useful Mortar Retainer for Building Blocks, of which the following is a specification.

This invention relates to improvements in devices for retaining the mortar within the joints between two adjacent hollow building blocks, such as used in wall constructions. Considerable difficulty has been experienced in the past in laying that type of building blocks which are formed hollow and provided with comparatively thin walls, due to the fact that the ends of the walls of the two adjoining blocks are comparatively thin, and it is difficult to place the mortar in between the said ends without too much of it running within the hollow portion of the blocks, which increases the expense of the wall construction.

Further, considerable difficulty has been experienced in retaining the mortar between the said ends after it has become dried due to the fact that the bond between the said mortar and the ends of the blocks is not very great and the thin layer of mortar sometimes falls out and especially if the wall settles slightly.

It is, therefore, the object of my invention to provide a device of simple, durable and inexpensive construction which may be inserted in the hollow spaces of the blocks near the adjoining ends, in such a manner that when mortar is placed between the ends of the blocks, it will not fall out or be squeezed into the hollow portions of the blocks before it is dried.

A further object is to provide means to assist in retaining the mortar between the ends of two adjoining building blocks after the said mortar has become dried, even if the bond between the mortar and the ends of the blocks should become broken.

A further object is to provide means to assist in spacing the blocks as they are being laid.

These and other objects will be apparent to those skilled in the art.

My invention consists in the construction, arrangement and combination of the various parts of the device, whereby the objects contemplated are attained, as hereinafter more fully set forth, pointed out in my claims,

and illustrated in the accompanying drawings, in which:

Figure 1 is a perspective view of my improved device.

Figure 2 is a side elevation of two building blocks arranged as they would be laid in a wall showing the manner in which my improved device is applied thereto before the mortar is placed in position.

Figure 3 is a detail, sectional view taken on the line 3—3 of Figure 2; and

Figure 4 is a detail, sectional view taken on the line 4—4 of Figure 2.

My improved device comprises a three-sided member which is formed of thin sheet metal and provided with a front member 10 and side members 11.

The front member 10 is provided with a notch 12 in its upper and lower edges, each of the side members 11 having their free ends pointed at 13, and its top edge provided with an upwardly extending flange 14, and its bottom edge with a downwardly extending flange 15. Each of these flanges is of a width substantially equal to the thickness of the mortar joint of a wall. The free end of each of the flanges 14 and 15 is provided with an outwardly extending curved portion 16.

The face of each of the members 11 is provided with V-shaped tongues 17 which are forced outwardly by means of a stamping die to form means for retaining the mortar. Any number of these flanges may be provided as is desired.

The flanges 17 are in line with the flanges 14 and 15, as clearly shown in Figure 1, and of a width not greater than the width of the said flanges.

In practical operation the device is used as follows:

Assuming that the block 18 has been laid in the wall and it is desired to place the block 19 in position adjacent thereto, the operator grasps one of the mortar retainers and inserts the pointed ends 13 into the opening of the block 18, until the flanges 14 and 15 engage the ends of the blocks. These flanges 14 and 15 are mounted in a vertical position. The block 19 is then grasped and placed in alignment with the block 18 and moved endways toward the block 18 with its opening over the front plate 12 until the ends of the block rest against the members 14 and 15.

Thus it will be seen that the movement

of the block 19 is limited toward the block 18 by means of the flanges 14 and 15, and thus provide means whereby the mason quickly spaces the blocks, and also alines

5 them laterally, due to the fact that the walls 11 hold the blocks in lateral alinement. He then forces the mortar into the spaces between the ends of the walls of the blocks and adjacent to the outer faces of the members 11. A portion of the mortar will be crowded back of the members 17 which will leave the said members 17 embedded in the mortar, as clearly shown in Figures 3 and 4, and between the curved portions 16. The 15 mortar may also flow between the abutting ends of the inner wall 20 of the double type of block, the inner walls 11 of the retainer preventing it from running into the openings of the blocks.

20 The notches 12 are provided in the upper edge of the front member 10 so the said front member may be inserted easily within the blocks even if projections extend inwardly, caused by cutting the blocks in two 25 when in a plastic condition.

Thus it will be seen that I have provided a simple device which when placed in position, as above described, will enable the mason to quickly and accurately lay blocks to 30 form a wall, and which will effect a considerable saving in mortar, due to the fact that none of it is permitted to run on the inside of the hollow blocks. This saving alone is almost sufficient to pay for the retainers.

35 It will also be seen that after the mortar has become set and dried, if the bond between the mortar and blocks should become broken, the said strips of mortar will not 40 fall out or become loosened.

I claim as my invention:

1. A mortar retainer for building blocks formed of a single piece of sheet metal having a front and parallel side members, each 45 of said side members being provided with a mortar retaining tongue, each of the upper and lower edges of said side members being

provided with a flange of a width equal to the width of the mortar joint, and of a height slightly less than the thickness of 50 the wall of the block.

2. A mortar retainer for hollow building blocks formed of comparatively thin metal having a front and side members, each of 55 said side members being provided with a spacing flange, and also provided with mortar retaining tongues in alinement with said flanges.

3. A mortar retainer for hollow building blocks formed of a bendable material comprising parallel side members spaced apart a distance equal to the distance between two opposite walls of a building block, of a width equal to the distance between the other two opposite walls of said block, and 60 provided with means for holding said members in fixed relation with each other, each of said side members being provided with a block spacing flange.

4. A mortar retainer for hollow building 70 blocks formed of a bendable material comprising parallel side members spaced apart a distance equal to the distance between two opposite walls of a building block, of a width equal to the distance between the 75 other two opposite walls of said block, and provided with means for holding said members in fixed relation with each other, each of said side members being provided with block spacing flanges, each of said flanges 80 being provided at its end with a curved portion, the said side members also being provided with a mortar retaining tongue in alinement with the said flanges, the free 85 ends of each of said side members being pointed.

5. A mortar retainer comprising parallel side members, and a front member, said front member having its upper and lower edges provided with a notch, each of said 90 side edges being provided with spacing flanges and mortar retaining tongues.

Des Moines, Iowa, April 17, 1922.

DAVID G. JOHNSTON.
